UNITED STATES PATENT OFFICE.

CHARLES FOWLER BALDWIN, OF MONTCLAIR, NEW JERSEY, ASSIGNOR, BY MESNE ASSIGNMENTS, TO WESTERN ELECTRIC COMPANY, INCORPORATED, A CORPORATION OF NEW YORK.

ELECTROMAGNET.

1,271,265.

Specification of Letters Patent

Patented July 2, 1918.

Application filed September 3, 1915. Serial No. 48,6

To all whom it may concern:

Be it known that I, CHARLES FOWLER BALDWIN, a citizen of the United States, residing at Montclair, in the county of Essex and State of New Jersey, have invented certain new and useful Improvements in Electromagnets, of which the following is a full, clear, concise, and exact description. This invention relates to electromagnets, 10 and more particularly to electromagnets provided with means for retarding the reaction of the same.

The object of this invention is to provide an inexpensive and efficient slow acting 15 electromagnet.

According to this invention a plurality of actuating windings are provided on the magnet core, one of said windings serving to retard the reaction of the magnet upon 20 the deenergization of another winding. The magnet may be adjusted in such a manner that by providing a high resistance actuating winding and a low resistance locking winding, the locking winding would 25 serve to retard the reaction of the magnet upon the deenergization of the high resistance winding. This arrangement is based on the well-known physical laws governing the reduction of the magnetic lines 30 of force when the current through the energizing winding is broken. If a magnet, on the core of which a single winding is provided, will release on one-third of its operating ampere turns in a certain interval, it 35 will require more time to release if one-sixth of its operating ampere turns is supplied by a second winding, the current through which is not broken until the magnet releases.

40 This invention is described and shown in the drawings as embodied in a selector circuit for automatic telephone exchanges. It will be obvious, however, that magnets constructed in accordance with the present in- 45 vention are adapted for use in circuit arrangements of widely varying character.

The invention will be more fully understood from the following detail description and the appended claims.

50 The calling subscriber located at substation 1, desiring to establish a connection with a called station 2, removes his receiver 55 from the switchhook, causing thereby, in the well-known manner, the selection of an

idle trunk leading to the selector switch 3 60 by means of a selecting mechanism 4. A circuit is established from grounded battery through the left-hand winding of a line relay 5, a wiper 6 controlled by a side-switch associated with selector 3, the calling or incoming line circuit, side-switch wiper 7 and the right-hand winding of relay 5, to ground. Relay 5 becomes energized and closes an energizing circuit from ground through its front contact, contact 8 (closed 65 as long as selector 3 is in its normal position), and the high resistance right-hand winding of a magnet 9, to grounded battery. Magnet 9 becomes energized and closes a locking circuit for itself from ground through its low resistance left-hand winding, left-hand front contact and armature, and the winding of a release magnet 10, to grounded battery. The current flowing 70 through this locking circuit is not of sufficient strength, however, to energize release magnet 10. The calling subscriber proceeds now to cause the setting of selector 3, in accordance with the numerical designation of the called substation, by operating a calling device 11 provided at substation 1. Upon each interruption produced in the line circuit, relay 5 closes a circuit from ground through its armature and back contact, side-switch wiper 12, the right-hand armature and front contact of magnet 9, a side-switch wiper 13, and the winding of a primary magnet 14 to grounded battery. Under the control of magnet 14 75 the brushes of selector 3 are moved in a 80 rotary direction.

Upon the first release of the armature of relay 5, the original energizing circuit of magnet 9 was opened. Magnet 9, however, does not become deenergized in response to 85 this short interruption produced in its energizing circuit, it being maintained actuated by the above traced locking circuit.

The left-hand winding of magnet 9 is composed of fewer turns than the right-hand winding, and is not strong enough to maintain the magnet locked up.

The magnetic flux due to the closure of the actuating circuit, including the right-hand winding, produces a potential in the locking 105 winding, said potential having the tendency to oppose the battery potential of the circuit including the left-hand winding. Upon a

interruption in the circuit, including the right-hand winding, the magnetic flux gradually collapses, but its reduction is retarded due to the effect of the additional field produced by the left-hand winding, whereby the retraction of the armatures of magnet 9 is retarded. The two windings are adjusted in such a manner with respect to each other that short current interruptions produced in the actuating winding will not result in the retraction of the armatures of magnet 9. It will be obvious to those skilled in the art that the magnet may be made slow to release by adjusting either its two windings or the electrical characteristics of the two circuits including said windings, in such a manner that upon an interruption of the actuating circuit the collapsing magnetic field is aided by the potential produced in the circuit of the other winding.

Magnet 14 stops the selector brushes, and, upon the completion of the first stop, this magnet closes its back contact as soon as the armature of line relay 5 disengages its back contact. Therefore, upon the second deenergization of relay 5 a circuit is established from ground through the armature and back contact of line relay 5, side-switch wiper 12, the right-hand armature and front contact of magnet 9, the armature and back contact of magnet 14, contact 15 (closed as soon as selector 3 leaves its normal position), and the high resistance right-hand winding of magnet 9, to grounded battery. Thus, during the vibration of the armatures of line relay 5 and primary magnet 14, the magnet 9 remains energized, the continuously closed locking circuit retarding the re-action of the magnet while the actuating circuit of the same is momentarily interrupted.

After the subscriber has sent out the desired series of impulses, the armature of line relay 5 is maintained attracted, and no circuit will be found for the high resistance winding of magnet 9, whereupon this magnet will slowly release. Upon the deenergization of magnet 9, the side-switch wipers are moved into position 2, in which position magnet 14 is disconnected, and a circuit is established from ground through an overflow contact 16 (open only if all the trunks in the selected group are busy), armature and back contact of a secondary magnet 17, side-switch wiper 18 and the winding of relay 19, to grounded battery. Relay 19 closes a circuit from ground through its armature and front contact, side-switch wiper 20, the right-hand back contact and armature of magnet 9, side-switch wiper 12, and the winding of magnet 17 to grounded battery. Magnet 17 becomes energized and opens the circuit of relay 19, which in turn causes the deenergization of magnet 17 and the reestablishment of its own circuit. It will be seen thus that magnet 17 is inter-

ruptedly energized and deenergized for causing the stepping of the selector brushes in a vertical direction.

As well known, the busy or idle condition of outgoing lines or trunks is determined by a potential placed upon multiple test terminals, such as 21. Supposing that in this case the busy condition of outgoing lines is characterized by a battery potential placed upon the test terminal 21, and the idle condition of such lines by a ground connection at terminal 21, it will be seen that as soon as an idle outgoing line is reached, a circuit is established from such ground through test terminal 21 and a test wiper 22 of selector 3, side-switch wiper 23, and the right-hand winding of escapement magnet 9 to grounded battery. Escapement magnet 9 becomes energized and moves now, upon its energization, the side-switch wipers into position 3 for disconnecting the secondary magnet 17 and connecting the calling incoming line at side-switch wipers 6 and 7 through to the selected outgoing line. The subscriber at substation 1 will cause now the complete establishment of the desired connection. In position 3 of the side-switch wipers, relay 5 and magnet 9 are deenergized.

Upon the severing of the established connection at the called station 2, a ground (which was disconnected after the seizure of an idle outgoing line by selector 3) is connected through test terminal 21, test brush 22, side-switch wiper 23, the left-hand back contact and armature of magnet 9, and the winding of release magnet 10 to grounded battery. Release magnet 10 becomes energized and closes a locking circuit for itself from ground through its right-hand armature and front contact, a contact 24 (closed as soon as selector 3 leaves its normal position), and the winding of this magnet to grounded battery. Under the control of magnet 10, selector 3 and the associated side-switch are restored to normal, the locking circuit for said magnet being maintained closed as long as contact 24 is closed, i. e., until selector 3 reaches its normal position.

There is shown at the left-hand armature of magnet 10 a well-known anti-sparking device comprising a condenser, a resistance and a grounded battery, which serves to prevent the sparking at the operating contacts of the magnets associated with the selector.

What is claimed is:

1. In a telephone exchange system, incoming lines, outgoing lines, a selector switch for interconnecting an incoming line with an outgoing line, a test brush, an impulse receiving means, a source of current, a plurality of operating magnets for said switch, a magnet for controlling the operation of said magnets, a winding on said controlling magnet arranged when energized to attract the armatures of said controlling magnet, and

other winding on said controlling magnet arranged when energized to retard the retraction of the armatures of said controlling magnet but unable to attract or maintain 5 said armatures attracted, means controlled by said impulse receiving means for completing a circuit for said first mentioned winding, means including the test brush for completing another circuit for said first mentioned winding, and means for completing a circuit for said second mentioned winding in series with said source of current.

2. In a telephone exchange system, incoming lines, outgoing lines, a selector switch for 10 interconnecting an incoming line with an outgoing line, a test brush, an impulse receiving means, a source of current, a plurality of operating magnets for said switch, a magnet for controlling the operation of said

magnets, a high resistance winding on said controlling magnet arranged when energized to attract the armatures of said controlling magnet, a low resistance winding on said controlling magnet arranged when energized to retard the retraction of the armatures of 20 said controlling magnet but unable to attract or maintain said armatures attracted, means controlled by said impulse receiving means for completing a circuit for said high resistance winding, means including said test 25 brush for completing another circuit for said high resistance winding, and means for completing a circuit for said low resistance winding in series with said source of current.

In witness whereof, I hereunto subscribe 30 my name this 28th day of August, A. D. 1915.

CHARLES FOWLER BALDWIN
